COMBINED LAST AND STRETCHER.

No. 366,888.

Patented July 19, 1887.

UNITED STATES PATENT OFFICE.

SAMUEL SCHWAB, OF WINDSOR, MISSOURI.

COMBINED LAST AND STRETCHER.

SPECIFICATION forming part of Letters Patent No. 366,888, dated July 19, 1887.

Application filed April 7, 1887. Serial No. 934,055. (No model.)

To all whom it may concern:

Be it known that I, SAMUEL SCHWAB, a citizen of the United States, residing at Windsor, in the county of Henry and State of Missouri, have invented certain new and useful Improvements in Combined Last and Stretcher; and I do declare the following to be a full, clear, and exact description of the invention, such as will enable others skilled in the art to 5 which it appertains to make and use the same, reference being had to the accompanying drawings, and to the letters and figures of reference marked thereon, which form a part of this specification.

15 This invention relates to a combined last and stretcher, and aims to provide a last which can be adapted to different-sized shoes, and which can be mounted upon a standard or not, as may be required, to devise provisions for stretching 20 any part or portion of a shoe, to contrive a means for forcing the last up into the toe of the boot or shoe, and, lastly, to produce a device for the purposes set forth which will be simple, compact, and economical as consistent 25 with the results to be attained.

25 The improvement consists in the novel features presently to be described and claimed, and shown in the annexed drawings, in which—

Figure 1 is a perspective view, parts being 30 broken away, of a combined last and stretcher constructed in accordance with and embodying my invention, mounted upon a standard; Fig. 2, a detail side view showing the manner of forcing the last into the toe of a boot or shoe;

35 Fig. 3, a rear view of the upper portion of the standard and last; Fig. 4, a plan view, parts being broken away, of the last, showing the stretcher-lever locked in position; Fig. 5, a

40 view, partly in section, showing the toe portion of the stretcher adjusted by dotted lines; Fig. 7, a view similar to Fig. 6, showing the instep portion adjusted by dotted lines; Fig. 8, a perspective detail of the toe portion of the

45 last, showing the filling-piece in position between the separated parts; Fig. 9, a perspective view of the filling-piece; Fig. 10, a perspective view of the stretching-block, which is applied to any portion of the last for stretch-

50 ing the shoe at any particular point; Fig. 11, an end view of the stretching-block; Fig. 12,

a transverse section of the last and stretcher on the line X X of Fig. 2. Fig. 13 are detail perspective views of the devices employed for stretching the shoe when the last is detached 55 from the standard. Fig. 14 is a perspective detail view of the front end of the last, showing a stretching-block in position; and Fig. 15, a perspective view of the heel-presser or device for forcing the last up into the shoe. 60

The last is composed of two longitudinal parts or halves, A and A', which are held together by the dowel-pins *a* and *a'*, and are adjusted to and from each other by the set-screws *a*² and *a'*², for widening and narrowing the last, 65 as desired, to adapt it to shoes of different width. The heel-piece C is adjustably connected with the last by the set-screw *c*, and is prevented from turning by the dowel-pin or guide *c'*, which is secured at its outer end to 70 the heel-piece, and has its inner end fitted in an opening in the last or one of the halves thereof. The last is lengthened and shortened by moving the heel-piece away from or nearer to the last, which is accomplished by turning the 75 set-screw *c* in the proper direction. A groove or recess is formed between the adjacent faces of the halves, in which is located the stretcher-lever B, which comes flush with the last, and is mounted upon the pivot *b'*, having each end 80 supported in the halves, one end being adapted to move relative to one part of the last, so the two parts can be separated or brought together. The front end of the lever terminates in the hook *b*, and the rear end is widened, and is 85 provided with the head *b*², having the opening or recess *b*³.

The stretcher D is concavo-convex and conforms to the instep and toe portion of the last over which in practice it is designed to fit, and 90 is held in place by the hook *b* of the lever B engaging with the eye *d*, depending from the toe of the stretcher. The stretcher and stretcher-lever are of about an equal length, and the rear end of the stretcher is notched, 95 whereby the two arms or lugs *d*' are formed, which are united at their outer ends by the cross-bar *d*². If the rear end of the lever is depressed, the toe portion only of the stretcher is forced out, thereby stretching the toe of the 100 shoe only. If the rear end of the stretcher is moved away from the last, the instep of the

shoe is stretched independently of any other part. By depressing the rear end of the lever and simultaneously moving the rear end of the stretcher away from the last the shoe will be stretched equally from toe to instep, as will be readily understood. These several results are accomplished by appliances and provisions more fully hereinafter specified.

The sides of the last and stretcher have openings or mortises c^2 at intervals for the reception of the shank e of the stretching-block E , which is inserted and held therein by the spring e' . For pegging or nailing the soles of shoes, mending heels, &c., the last is mounted upon the standard F and the shoe is held to the last by the strap G , in the usual manner. The lower end of the strap is connected with the lever H by the hook g . The rear end of the lever is held down by the lip h , secured to and projecting from the side thereof, engaging with one of the teeth of the ratchet-plate h . The upper end of the standard is bifurcated, forming lugs f , which embrace the heel or tongue A^2 of the last. The lower end of the tongue is rounded and the upper ends of the lugs f are correspondingly rounded, so that when the parts are placed together and connected by the pin i' a rule-joint will be formed. The lower rear side of the tongue is notched and forms the shoulder or stop a^4 , against which the end or shoulder on the rod J abuts and limits or prevents any tilting up of the last. The last is held from tipping down by the stops f' , projected from the forward side of the standards, which stops come directly beneath the last on each side of the head b^2 of the lever B . The rod J is fitted in a groove formed in the rear of the standard, and is pivoted therein near its lower end. The set-screw J' , passed through the cross-bar j , bears upon the lower end of the rod for forcing said end within the groove and the upper end correspondingly outward. The upper end is provided with the extension j' , which is fitted to the heel-presser J^2 , having the socket j^2 at its lower end to receive the extension j' .

For forcing the last up into the toe of the shoe, the heel-presser is adjusted upon the end of the rod and the set-screw J' is screwed in, which forces the lower end of the rod J in and its upper end out, and the heel-presser bearing upon the interior of the shoe forces the shoe toward the rear and upon the last, as will be readily understood. The lugs or brackets $F' F'$, projected from the standard, form bearings for the adjusting-screw K , having the handle k at its lower end, by which the screw is rotated in its bearings. The nut L , mounted upon the screw, is guided in its vertical movements by the rod l , secured at each end to the standard. The nut L forms a carrier for the rod M , which is pivotally connected at its lower end therewith. The rod M works in the groove m in the standard, and is provided at its upper end with the hook m' , which is adapted to engage with the cross-bar d^2 of the stretcher and

to draw the rear end of the stretcher down or bear upon the rear end of the lever B and force said end in and the opposite end accordingly outward. The spring N holds the rod m close up against the standard. The base I is centrally apertured and the lower end of the standard F is mounted therein so as to turn. The last can be readily detached from the standard and yet be used for stretching shoes. To effect this result, the hand-screw K' , corresponding to the screw K , is provided, and the end is reduced, so as to fit the opening b^3 in the head of the lever B , which enters said end of the screw. The yoke O is mounted upon the screw, and its ends, which are hook-shaped, pass through the brackets p , projected from and connected with each side of the last. By screwing down upon the lever B the toe portion of the stretcher will be moved outward. Now disengaging the ends of the yoke from the brackets and fastening the lever by a pin passed through the opening a^5 , and screwing down upon the lever, as before, the rear end of the stretcher will be moved out. If the pin be removed and the screw turned down, the stretcher will be forced out at each end. The stretching-blocks E are used only in case it be desired to stretch the shoe at a particular spot, so it will not bear upon a callous portion of the foot, such as a corn, bunion, &c.

In case a shoe is very wide and a large space would be left between the parts of the last near the toe the filling d is provided, which has ribs g on its sides to fit corresponding grooves in the sides of the halves.

Having thus described my invention, what I claim, and desire to secure by Letters Patent, is—

1. The combination, with the last longitudinally grooved, of the lever fitted in said groove and extending flush with the last, the stretcher concavo-convex in form and adapted to fit over said lever, and provisions, substantially as set forth, for moving said stretcher, as and for the purpose specified.

2. The combination, with the last divided longitudinally and the parts adjustable to and from each other, of the lever located between the parts, the stretcher fitted over the lever and adjustable to and from the last, whereby the last can be accommodated to shoes of different size.

3. The combination, with the last composed of two longitudinal halves adjustably connected together, the lever, and the stretcher, of the heel-piece adjustably connected with the last, whereby the last can be increased in width and thickness and length, substantially as set forth.

4. The combination, with the last composed of two longitudinal halves adjustably connected together, of the filling-piece, as d , inserted between the halves, substantially as and for the purpose described.

5. The combination, with the halves of the

last having grooves in their adjacent faces, of the filling-piece having corresponding ribs to fit in the grooves, substantially as described.

6. The combination, with the last, of the 5 stretching-blocks having shanks and locking-springs for holding the blocks in position, substantially as set forth.

7. The combination, with the last, the standard, and the heel-presser, of the rod pivoted 10 between its ends, and having one end connected with the heel-presser, and means, as the set-screw, for moving the free end of the rod, whereby the heel-presser is forced away from the last, substantially as and for the purpose 15 described.

8. The combination, with the standard, the last pivoted upon the top thereof, and having a stop, of the rod pivoted to the standard and adapted to engage with the stop and lock the 20 last against turning, substantially as set forth.

9. The combination of the standard, the last pivoted upon the top of the standard, the heel-presser, and the rod pivoted between its ends, said rod forming a lock to hold

the last against turning, and also as a support 25 for the heel-presser, substantially as described.

10. The combination, with the last, the lever, and the stretcher, of the standard, the screw, the carrier-nut, and the rod connected at its lower end with the nut and adapted to 30 have its upper end connected with the stretcher or bearing upon the rear end of the lever, substantially as set forth.

11. The combination, with the last, the lever, and the stretcher, of the standard, the screw 35 mounted in brackets projected from the standard, the guide-rod, the carrier-nut mounted upon the screw, the rod pivotally connected at its lower end with the nut and terminating at its upper end in a hook, and a spring for 40 holding the rod close against the standard, substantially as described.

In testimony whereof I affix my signature in presence of two witnesses.

SAMUEL SCHWAB.
